CLAIM

The ornamental design for an electronic fragrance emitter, as shown and described.

DESCRIPTION

FIG. 1 shows the top, front, right side perspective view of an ornamental design of an electronic fragrance emitter according to an exemplary embodiment of the invention.

FIG. 2 shows the bottom, back, left side perspective view thereof.

FIG. 3 shows the front elevation view thereof.

FIG. 4 shows the back elevation view thereof.

FIG. 5 shows the top plan view thereof.

FIG. 6 shows the bottom plan view thereof.

FIG. 7 shows the right side elevation view thereof, the left side elevation view being a mirror image thereof.

FIG. 8 shows the top, front, right side perspective view of an ornamental design of an electronic fragrance emitter according to an alternate exemplary embodiment of the invention.

FIG. 9 shows the bottom, back, left side perspective view thereof.

FIG. 10 shows the front elevation view thereof.

FIG. 11 shows the back elevation view thereof.

FIG. 12 shows the top plan view thereof.

FIG. 13 shows the bottom plan view thereof; and,

FIG. 14 shows the right side elevation view thereof, the left side elevation view being a mirror image thereof.

Shading lines are used to show solid structures and are not intended to indicate surface decoration. Dashed lines are used to show environment and form no part of the claimed design.
